UNITED STATES PATENT OFFICE.

NILS EMERT, OF OMAHA, NEBRASKA.

COMBINED POCKET-BOOK AND SATCHEL LOCK.

SPECIFICATION forming part of Letters Patent No. 511,765, dated January 2, 1894.

Application filed September 14, 1891. Serial No. 405,671. (No model.)

To all whom it may concern:

Be it known that I, NILS EMERT, a citizen of the United States, residing at Omaha, in the county of Douglas and State of Nebraska, have invented certain new and useful Improvements in a Combined Pocket-Book and Satchel Lock, &c., and I do declare the following to be a full, clear, and exact description of the invention, such as will enable others skilled in the art to which it appertains to make and use the same, reference being had to the accompanying drawings, and to the letters of reference marked thereon, which form a part of this specification.

My improvement consists in a combined pocket book and satchel lock, making a secure and reliable fastening for pocket books, valises and traveling bags constructed with a frame having two parts or jaws, each part having a recess on the inside in which are located hooks, springs, a slide and a cam. The springs and slide are operated by means of push-buttons located on the outside of frame locking and unlocking the device without the use of a key.

Figure 1. represents a pocket book or money bag with frame closed. Fig. 2. represents the frame and different parts of lock. Fig. 3. represents lock and different parts. Fig. 4. gives end view of frame and lock open. Fig. 5. gives end view of frame and lock closed. Fig. 6. shows inside of lock.

Similar letters refer to similar parts throughout the several views.

A, represents the frame.

b, b² and c, represent three springs used.

o, represents the notch near end of spring b.

p represents a notch near end of spring b².

See Fig. 6.

a and a² are the hooks.

d represents a slide.

g, refers to end of slide which locks spring b.

f represents the end of slide which makes contact with spring c.

The push-buttons are marked x, y, z, and z².

The frame of this lock consists of two parts or jaws which work with a hinge at each extremity Fig. 4, and having a recess on the inside in which are located the locking devices. The spring b, is a long narrow piece of spring steel one extremity of which is riv-

eted to one section or jaw of the frame, Fig. 3,—the other extremity of the spring being left movable and having a notch at o, see Fig. 6 at which point the spring receives hook a² 55 on closing the pocket book, the hook passing under the spring at a right angle and having a flaring point such that when it comes in contact with the spring it presses the spring out of position, sufficient to allow the end of the hook to pass by it, and when the pocket book is fully closed the spring flies back into the book, holding the frame closed; and when said spring and hook are thus engaged the spring is held into the hook a² or locked by 60 means of slide d, the end of which marked g, is constructed narrow and wedge shaped, and is moved over the end of spring b, passing between said spring and the inner surface of the frame filling the space between spring and 70 frame, locking the spring as described. When slide d, is thus adjusted over spring b, slide d, is held in this position by means of spring c, which drops behind it making contact with end of d, marked f, see Figs. 3 and 6, which end 75 of slide has a square shoulder, which receives the end of c' which also has a square shoulder thus locking slide d, Figs. 3 and 6, the end of spring c, remote from slide d, being riveted to the frame, the end of c, coming in contact with d, being movable and operated by push button x, which is attached to the spring by a short shaft extending through an oblong slot in the frame. Slide d, is moved back and forth by means of push button z² which is attached to the slide by a short shaft extending through an oblong slot in the frame. 80

Slide d, is moved back and forth by means of push button z² which is attached to the slide by a short shaft extending through an oblong slot in the frame. Spring b, is raised out of the hook a² by means of push button z, which is attached to the spring by a short shaft, extending through an oblong slot in the frame. 85

To unlock said device raise spring c, which allows removal of slide, from over spring b, the end of slide d, marked f, passing under c, then raise spring b, out of hook a². Hook 95 a² is made solid to the opposite jaw of frame, from that containing the spring b. The other section or jaw of frame A, contains spring b², one end of which is riveted to the frame, the other extremity remaining movable, and having a notch at p, at which point the spring receives hook a on closing the 90 100

frame in like manner as spring b , attaches to hook a^2 . Spring b^2 when frame is closed is held or locked into hook a by means of cam e , which is turned over said spring by means 5 of button x , which is also used as turn button, said cam e , passing between said spring and inner surface of the frame filling the space and making a perfect and secure lock of spring b^2 and hook a . To unlock same, 10 cam e , is turned from over the spring b^2 then raising the spring out of hook a , by means of push button y , which is attached to said spring by a short shaft extending through a slot in the frame.

15 On the sides and upper surfaces of frame are placed other stationary buttons of same form and size as those attached to the springs and slide, which are for the purpose of making the discovery of the combination of the 20 lock more difficult.

All the springs are made of such strength and tension as to be easily operated by the fingers, pushing upon the buttons named.

Having fully described my invention, what

I claim, and desire to secure by Letters Patent 25 of the United States, is—

A combined pocket book and satchel lock consisting of two pivotally connected jaws, provided with external push buttons x , y , z , and z^2 one of said jaws provided with a 30 spring b , connected to push button z , and provided on its movable end with a notch o ,—a wedge shaped slide d to hold spring b , in its position, operated by push button z^2 , and spring c , adapted to be moved by button x , 35 which holds slide d , in its moved position, the other of said jaws being provided with a spring b^2 , connected to push button y , and provided on its movable end, with a notch p , adapted to engage hook a on the other jaw, 40 which spring is locked by cam e and a hook a^2 adapted to engage in the notch of spring b^2 , substantially as described.

NILS EMERT.
